UNITED STATES PATENT OFFICE.

SAMSON D. WRIGHT, OF CLEVELAND, OHIO.

DUMP-CAR.

1,105,948.

Specification of Letters Patent.

Patented Aug. 4, 1914.

Application filed February 9, 1910. Serial No. 542,932.

To all whom it may concern:

Be it known that I, SAMSON D. WRIGHT, a citizen of the United States, residing at Cleveland, in the county of Cuyahoga and 5 State of Ohio, have invented certain new and useful Improvements in Dump-Cars, of which the following is a specification.

This invention relates generally to improvements in dump cars and more particularly to the class of dump cars, termed "coke quenching" cars, and in using this type of cars the hot coke is discharged from the ovens directly into these cars where it is quenched by water, and it is necessary that 10 they should be constructed so that they should be able to stand the intense heat and that some provisions should be made for expansion and contraction due to changes in temperature, and further that they should 15 be constructed so as to prevent the loss of fine particles of coke, termed "breeze".

More specifically the invention relates to a coke quenching car having a portion, which is subjected to the greatest heat, made 20 up or formed of flanged cast metal plates which will stand the intense heat of the coke and will quickly radiate the heat through its flanges.

Invention also resides in connecting and 25 supporting cast bottom plates in a manner such that they may expand and contract freely relative to each other in the plane of the floor of the car due to changes in temperature resulting from the intense heat of the 30 coke as it comes from the ovens and to the cooling action of the water which is projected upon it.

Still further invention resides in arranging 35 all of the plates and the doors in a manner such that all fine particles of coke, termed "breeze", may be kept within the car and prevented from washing away.

Invention further resides in certain details of construction hereinafter set forth 40 in the following description, drawings and claims.

In the drawings, Figure 1 is a perspective view of a portion of a car constructed according to my invention; Fig. 2 is an end 45 elevation; Fig. 3 is a sectional view; Fig. 4 is a plan view of the bottom; Fig. 5 is a

section upon the line 5—5 of Fig. 4 looking in the direction indicated by the arrows; Fig. 6 is a section upon the line 6—6 shown in Fig. 4 and looking in the direction indicated by the arrows; Fig. 7 is a side elevation of a modified form of car; Fig. 8 is a vertical transverse sectional view taken to one side of the shedding plates shown in Fig. 7, and broken away in parts to 60 more clearly show details; Fig. 9 is a top plan view of the bolster set forth in side elevation in Fig. 8; and Fig. 10 is a section taken upon the line 10—10 of Fig. 8 looking in the direction indicated by the 65 arrows.

In carrying out the invention any preferred form and construction of a car may be arranged according to the teachings of my invention, but I have shown one form 70 in the drawings which meets the requirements very effectively, and in such embodiment, 15 represents one of the trucks, which may be of any desired construction, and is mounted under the bolster 16 in the usual 75 manner. The bolster 16 is preferably made up of a main body portion having flanges 17 which are bolted or otherwise secured to the left-hand sill 18 which may be of the ordinary construction but is preferably made 80 of channels placed back to back. The opposite end of the main portion of the bolster is provided with flanges 19 which are secured against the web of the other sill 20 which, in this instance, is placed inside of 85 the wheel, as shown in Fig. 3, for accommodating the peculiar car body. This sill 20 is made up of channels placed back to back. The bolster 16 consists of another portion 21 shown in Fig. 8, and extending out beyond 90 the wheels. This portion is inclined downwardly at the top and is provided with flanges 22 shown in dotted lines in Fig. 9 and secured against the web of sill 20 so as to form a continuation of the main body 95 portion of the bolster, and by this two-piece arrangement the sill 20 is permitted to pass through it in a solid structure at this point, it being necessary to place the sill 20 within the ends of the bolster in order to accommodate the structure of the car body. In order 100 to insure a rigid structure for the bolster a

bridge piece 23 is provided, and it comprises a web 24 and upper and lower flanges, the latter being secured by bolts to the two sections of the bolster as shown in Fig. 8.

5 This member is inclined as shown in this figure to conform to the configuration of the end portion 21 of the bolster.

So far the description has been confined to the lower frame structure of the car and has been described with particular reference to the bolster and the sill arrangement and the point of invention in this part of the structure lies in the arrangement of a sill passing between portions of a divided bolster, together with means for insuring a rigid structure in the divided bolster.

Secured to the sill 18 are supports 25 which extend vertically above the sill and at the upper end support a suitable channel 26 extending along the side and throughout the length of the car. The sill 20, on the other hand, has secured to its upper flanges brackets 27 having inclined faces, and these brackets 27 and the channel 26 support intermediate rails 28 having flanges 29 to which the floor of the body is secured. At each end of the car an angle rail 28' is arranged, as shown in Figs. 1 and 2, for supporting the bottom or floor at this point.

30 There are several of these rails throughout the length of the car and the number may be varied as desired. The sill 20 also supports, at each end of the car, an upright 30 secured at its upper end to a transverse end channel

35 31 which extends out beyond the side of the trucks on one side and at its opposite end is secured to one of the uprights 25. A diagonally disposed channel 32 extends from a point near the base of the upright 30 to the 40 overhanging end of each channel 31 where it extends out beyond the side of the trucks as shown. To these same ends of the channels 31, which extend beyond the sides of the trucks, are secured upright angle members

45 33, and these members are connected at their upper ends to inclined angle bars 34 which extend down transversely of the car to the opposite ends of the end channels 31. A suitable end plate 35 of sheet metal is se-

50 cured to these members and forms the ends of the car above the end channels 31. A side sheet metal plate 36 forms the side of the car above the plane of the end channels 31 and it is extended below this point for a 55 purpose to be described.

The lower structure of the car including the ends and the bottom or floor is made up of cast plates and these will now be described. Each end is made up of a cast plate 60 37 closing the space formed by the upright 30, the end channel 31 and the angle rail 28', while a cast plate 38 closes the space formed by the upright 30, the end channel 31 and the diagonal channel 32. These plates are 65 provided with suitable webs on the outside

to give strength but more particularly to radiate heat from the end plates. Another suitable cast end plate 39 is secured to a portion of the angle rail 28' to the diagonal upright 32 and to the downwardly projecting portion of the side plate 36. This plate is likewise provided with radiating flanges.

The bottom of the car is inclined as shown and is made up of three longitudinally disposed rows of cast plates 40 all provided with radiating flanges 40' on the under side. These plates are arranged so that their main body portions are a short distance apart at their adjacent edges and at their lateral adjacent edges one has an extension or flange 42, as shown in Figs. 5, for projecting over the extension 43 of the next adjacent plate, and this flange and extension construction is maintained at all the seams in the floor of the car.

85 The flange of each plate is provided with elongated openings 44 to receive bolts 45 which pass through counter-sunk openings 46 in the projection of the next adjacent plate, and through openings in the rails 28 and 28'.

The object of this arrangement is that there may be lateral expansion and contraction between the plates due to changes in temperature. It is understood that normally the plates are connected by the bolts 45 so that they may move relatively in the plane of the floor, as shown clearly in Fig. 4, in order that expansion and contraction may take place.

At the transverse adjacent edges one plate is provided at its edge toward the lower edge of the bottom or floor with an overhanging projection 47 similar to the lateral projections 43 and these are adapted to lap over flanges 48 extending from the edge of the next adjacent lower plate, this flange 48 being lower in each instance than the upper surface of the plate, so that the upper surfaces of all plates may be flush with each other. The flanges 48 are provided also with elongated openings 49 for receiving bolts 50 which pass through counter-sunk openings 51 in the projection 47.

When the plates are in normal position there is space between adjacent edges so that expansion and contraction may take place transversely. The upper edges of all of the plates along the upper edge of the bottom or floor of the car are provided with downwardly projecting flanges 52 which engage the flanges of the rails 28 and the angle rail 28', while the lower plates 40 at the lower edge of the bottom are provided with shoulders 53 which align and form a ridge, as it were, longitudinally of the car and also form a long flat portion 54 which serves to carry the material beyond the trucks and oil boxes and well out from the side of the car. This flat portion 54 is provided with openings 55 for a purpose to be described.

Hinged to the downwardly projecting por- 130

tion of the side plate 36 are suitable doors 56 of cast metal having upon the lower inner edge thereof a wear strip 57 which is adapted to engage the shoulder 53 formed on the lower floor plates. These doors are held against this shoulder by means of gravity latches 58 pivoted under the car and swinging up through the openings 55. There are several doors, four in the present case, throughout the length of the car, and there are two latches for each door, one being located near each end.

In the modification shown in Figs. 7, 8 and 10, the car is provided with a similar bottom structure and upper structure, but the overhanging side plate is brought down sufficiently so as to connect with an upper chute member 59. The doors 60, in this instance, are mounted on segments 61 pivoted on suitable pins 62 secured to transversely disposed shedding plates 63 bolted to the bottom of the car and having shed-like upper portions 64 which are clamped on either side of a bracing web plate 65 secured to the side plate and to the bottom of the car. These shedding plates serve to make a housing for the segments 61 of adjacent doors and they are continued out between the bottom and the chute member 59 so as to complete the chute formation at each door. Pivoted in suitable brackets or ears 66 secured to the upper edge of each door is a link 67 which has its other end pivoted in suitable ears 68 carried by a cross head 69 mounted upon vertically disposed guides 70. This cross head has an arm 71 projecting therefrom and adapted to be engaged by any suitable lifting mechanism, not shown. The chutes, formed at each door, as shown in Fig. 7, are slightly less in length than the length of each door whereby the segments 61 are arranged outside of the chutes, and within the housings formed by the shedding plates 63. In the type of car set forth in the drawings, a little more than half of the car being shown in Fig. 7, there are four doors so that there will be four chutes, and the supporting segments for these doors will be arranged in the housings formed at the three points within the length of the car, the end segments for the two end doors being outside of the ends of the chutes toward the ends of the car.

Having described my invention, I claim:—

1. In a dump car, in combination, suitable trucks, a framework mounted upon said trucks, a body, and a floor comprising a plurality of cast plates supported on the framework to have free expansion with respect to each other and to have movement bodily in the plane of the floor.
2. In a dump car, in combination, suitable trucks, a framework mounted upon said trucks, a body mounted upon said framework, and a floor comprising a plu-

rality of cast plates supported upon the framework, and having connections between them and with the framework to permit expansion and contraction of the plates and bodily movement in the plane of the floor. 70

3. In a dump car, in combination, suitable trucks, a framework mounted thereon, a car body mounted on the framework, a floor mounted upon the framework in the bottom of the body, said floor being composed of cast plates having overlapping joints permitting free expansion and contraction of one plate with respect to the other, and means securing the plates to the framework and permitting bodily movement of the plates in the plane of the floor. 80

4. In a dump car, in combination, suitable trucks, a frame mounted thereon, a body supported by said frame, and a floor mounted in said body upon the frame and comprising a plurality of cast plates having slidable lap joints permitting each plate to expand and contract with respect to the adjacent plate in the plane of the floor, and means securing said plates to the frame and 90 permitting bodily movement of the plates in the plane of the floor.

5. In a dump car, in combination, suitable trucks, a frame mounted thereon, a car body on said frame, a floor for said body and composed of a series of plates having overlapping portions at their adjacent edges, such overlapping portions being provided with openings, the opening of one portion being larger than the opening in 100 the corresponding portion, bolts passing through such openings for securing the plates together but permitting them to move in the plane of the bottom of the car relative to each other, supporting members for 105 said floor, means for securing said floor to said supporting members, and suitable dumping doors.

6. In a dump car, in combination, suitable trucks, a frame mounted thereon, a car body on said frame, a floor for said body and composed of a series of plates having overlapping portions at their adjacent edges, such overlapping portions being provided with openings, the opening of one 110 portion being larger than the opening in the corresponding portion, bolts passing through such openings, for securing the plates together but permitting them to move in the plane of the bottom of the car relative to each other, transversely disposed rails secured to the framework, means for securing the floor to the rails, and suitable dumping doors. 115

7. In a dump car, in combination, suitable trucks, a frame mounted thereon, a car body on said frame, an inclined floor for said body and composed of a series of plates having overlapping portions at their adjacent edges, such overlapping portions being 120 125 130

provided with openings, the opening of one portion being larger than the opening in the corresponding portion, bolts passing through such openings for securing the plates together but permitting them to move in the plane of the bottom of the car and relative to each other, inclined, transversely disposed supporting rails secured to the frame,

means for securing the floor to the rails, and suitable dumping doors.

In testimony whereof I affix my signature in presence of two witnesses as follows:

SAMSON D. WRIGHT.
